UNITED STATES PATENT OFFICE.

HENRY MARVIN OZMENT, OF SCHOOLFIELD, VIRGINIA.

LOOM PICKER-HEAD.

1,369,046.

Specification of Letters Patent. Patented Feb. 22, 1921.

Application filed February 25, 1920. Serial No. 361,137.

To all whom it may concern:

Be it known that I, HENRY MARVIN OZMENT, a citizen of the United States, and a resident of Schoolfield, in the county of 5 Pittsylvania and State of Virginia, have invented certain new and useful Improvements in Loom Picker-Heads, of which the following is a specification.

My invention relates to loom picker heads 10 of that type which is comprised of laminations of leather. I have found in heads of this character that after a brief period of use they become torn and distorted under the action of the shuttle and are thus rendered useless.

It is a purpose of my invention to materially prolong the life of usefulness of picker heads of this character by interposing a plate of metal, preferably steel, between the laminations in such manner that the entire head as a unit is reinforced against the detrimental action of the shuttle. At a point corresponding to that point at which the shuttle abuts the picker head, 25 the plate is provided with an orifice which allows of the free and unrestricted movement of the shuttle without blunting its point, at the same time insuring a uniform wearing of the several layers of leather so that the possibility of the shuttle tearing the layers apart as in the usual form of head is eliminated.

I will describe one form of plate embodying my invention and will then point out the 30 novel features thereof in the claim.

In the accompanying drawings:

Figure 1 is a view showing in perspective one form of picker head having applied thereto the plate embodying my invention. 40 Fig. 2 is a transverse sectional view taken on the line 2—2 of Fig. 1.

Fig. 3 is a detail perspective view of the plate.

Referring specifically to the drawings in 45 which similar reference characters refer to similar parts, L designates the several layers of leather comprised in the picker head, the uppermost layer being formed with a recess 15 in which the shuttle point engages 50 the picker in the normal operation of the

shuttle. Interposed between the layers L at a point adjacent the top side of the picker head is the plate designated at P, such plate being coextensive in length with the head and of a width less than that of the layers as 55 indicated in dash lines in Fig. 1. As shown in Fig. 3, the plate P is of the general outline as that of the layers L and is provided at a point adjacent one end thereof with an opening 16. The several layers L are provided with similar openings at corresponding points, all of such openings being designed for the purpose of receiving a rivet R for securing the several layers and the plate together. At a point intermediate its 60 ends, the plate P is formed with an orifice 17 which in the applied position of the plate as shown in Figs. 1 and 2 is disposed directly below the recess 15. By this arrangement of the orifice, it will be seen that after the 65 shuttle point is worn through the layers of leather above the plate P, it is free to continue the wearing of the remaining layers by virtue of the orifice. The orifice 17 is of sufficient size to allow of the ready passage 70 of the shuttle point therethrough.

Although I have herein shown and described only one form of picker head and one form of plate embodying my invention, it is to be understood that various changes 80 and modifications may be made herein without departing from the spirit of the invention and the spirit and scope of the appended claim.

What I claim is:

A loom picker head formed of laminations of flexible material, a rigid metallic plate interposed between certain of the laminations and of the general configuration as the laminations, said plate being formed 90 with an opening at the point at which the shuttle is adapted to engage the picker head, and a rivet extending through one end of the laminations and through the adjacent end of said plate. 95

HENRY MARVIN ^{his} X OZMENT.
